US0D1077902S

(12) **United States Design Patent** (10) **Patent No.:** **US D1,077,902 S**
(45) **Date of Patent:** **** Jun. 3, 2025**

(54) **MOBILE PAYMENT POS MACHINE**

(71) Applicant: **PAX COMPUTER TECHNOLOGY (SHENZHEN) CO., LTD.**, Guangdong (CN)

(72) Inventors: **Shaowen Luo**, Guangdong (CN); **Wei Qin**, Guangdong (CN); **Haibin Guo**, Guangdong (CN)

(73) Assignee: **PAX COMPUTER TECHNOLOGY (SHENZHEN) CO., LTD.**, Guangdong (CN)

(**) Term: **15 Years**

(21) Appl. No.: **29/862,188**

(22) Filed: **Dec. 7, 2022**

(30) **Foreign Application Priority Data**

Sep. 21, 2022 (CN) 202230624649.6

(51) LOC (15) Cl. **08-01**

(52) U.S. Cl.

USPC **D18/4.6**

(57) **CLAIM**

The ornamental design for a mobile payment POS machine, as shown and described.

DESCRIPTION

FIG. 1 is a top, front and right side perspective view of a mobile payment POS machine, showing our new design; FIG. 2 is a bottom, rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines are included to show features that form no part of the claimed design.

1 Claim, 8 Drawing Sheets
